UNITED STATES PATENT OFFICE

2,580,712

CONTAINER FOR PACKAGING
MERCANDISE

Abraham E. Weisberg, New York, N. Y.

Application June 3, 1949, Serial No. 96,943

1 Claim. (Cl. 229—53)

1

My invention is directed toward a highly improved construction for containers for packaging merchandise.

The types of containers or bags heretofore manufactured of transparent materials have been found to possess many inherent disadvantages which render them undesirable. For example, when such containers are made entirely of the product known as "Pliofilm" or the like, while effective and useful for many purposes they are undesirable for loading textiles, notions and novelties since they have no firm body and therefore collapse easily. Containers made of transparent cellulose and similar materials have been found to be undesirable because they tend to shrink or dry out, and become distorted. They also tend to become brittle in cold weather and consequently cannot stand continuous use.

It is therefore one of the principal objects of my invention to provide a container for packaging merchandise which will overcome the above described disadvantages of the containers heretofore used and which will at the same time possess additional advantageous features.

Another object of my invention is to provide a container for merchandise which shall be rugged, transparent and yet which will maintain its shape, thereby making it easy to fill and to empty and which at the same time shall be relatively inexpensive to manufacture and economical to use.

Other objects of my invention will become apparent from the description of the invention to follow, or will hereinafter be more particularly pointed out.

In the accompanying drawings,

Fig. 1 is a front elevational view of a container for merchandise, constructed and arranged in accordance with my invention;

Fig. 2 is an enlarged cross-sectional view taken substantially along the line 2—2 of Fig. 1;

Fig. 3 is an enlarged cross-sectional view taken substantially along the line 3—3 of Fig. 1; and

Fig. 4 is an enlarged cross-sectional view taken substantially along the line 4—4 of Fig. 1.

Referring now in detail to the drawings, I have shown a container for merchandise, in the form of a bag 10 constructed and arranged in accordance with my invention and comprising a first wall 11 having top, side and bottom peripheral edges 11a, 11b and 11c respectively, and a second wall 12 having top, side and bottom peripheral edges 12a, 12b and 12c respectively.

In accordance with my invention the first wall 11 is preferably made of a sheet of transparent

2

material which possesses a certain degree of rigidity and body, such as for example, material on the nature of "Glassine" or other similar paper material. The second wall 12 is preferably made of a sheet of less rigidity than the wall 11 and more transparent, such as, for example, the material known as "Pliofilm," which is a rubber hydrochloride.

It is noted that the wall 11 is of a predetermined size and that the wall 12, although coextensive therewith in its vertical or longitudinal dimension, is made wider than the wall 11 in its horizontal or transverse dimension as clearly shown by the dotted line portions 14 in Fig. 2 of the drawings. In assembling the bag 10 a layer of adhesive material 15 is placed on one surface of the wall 11 adjacent the side marginal edges 12b. A layer of adhesive 20 is also placed along the bottom marginal edge 12c but on the opposite surface from that of the layer of adhesive 15. The area adjacent the bottom coextensive edges 11c and 12c are pressed together to seal off the bottom. The overhanging portions 14 of the wall 12 are then folded inwardly around the peripheral edges 11b to overlie the surface of the wall 11 and pressed against the adhesive layer 15, to form a bag which is sealed at the sides and bottom and open at the top. To provide a better seal for the bottom and to further reinforce the corners thereof, a portion of the superimposed walls 11 and 12 adjacent the bottom of the bag 10 is folded over on itself as shown by the dotted line portions 11' and 12' in Fig. 3 and permanently held in such folded over condition by a layer 25 of adhesive, as clearly shown in the said Fig. 3. As noted in Fig. 4, by reason of the above construction, the corners of the bag 10 are doubly reinforced.

It will thus be seen that I have provided a container for packaging merchandise which achieves the several objects of my invention and is well adapted to meet the conditions of practical use.

As various possible embodiments might be made of the above invention, and as various changes might be made of the embodiments above set forth, it is to be understood that all material herein described or shown in the accompanying drawings is to be interpreted as illustrative and not in a limiting sense.

50 I claim:

55 A container of the character described for packaging merchandise comprising a first wall formed from a sheet of rubber hydrochloride or the like, having a relatively low degree of rigidity and having a predetermined peripheral contour, a sec-

ond wall formed from a sheet of transparent paper material or the like, having a relatively greater degree of rigidity than said first wall and having a peripheral contour similar to that of said first wall, means for sealing adjacent marginal edges of said first and second walls throughout except for a predetermined portion to provide an opening for the insertion and removal of merchandise, said first and second walls being coextensive in the direction of one of their axes, said first wall having a greater dimension than said second wall in the direction of their other axes to provide said first wall with portions extending beyond opposite edges of said second wall, said last named extending portions of said first wall being folded over inwardly around substantially the peripheral edge of said second wall to overlie said second wall and a portion adjacent the sealed coextensive edges of said walls being turned over on itself and adhesively attached to said container whereby to further reinforce said coex-

tensive edges of said walls and whereby the wall having a greater degree of rigidity will support the less rigid wall and thus prevent the container from collapsing while being filled.

ABRAHAM E. WEISBERG.
